DIE BLOCK FOR WIRE DRAWING MACHINES

Ray C. Kivley, Kenmore, N. Y., assignor to
Western Electric Company, Incorporated, New
York, N. Y., a corporation of New York

Application October 4, 1950, Serial No. 188,444

4 Claims. (Cl. 205—25)

1

This invention relates to die blocks for wire drawing machines and has for its object an open structure rendering the dies more accessible and permitting freer circulation of the drawing compound.

In conventional wire drawing machines, particularly those employed for the final drawing operations, stepped capstans control the advancement of the wire longitudinally in paths where the reducing dies are placed. Several dies are employed in machines of this type and as a rule they are fixedly mounted in holders which completely surround the dies and become a part of the die block. During the operation of wire drawing machines, a suitable wire drawing compound flows over the support for the dies and other portions of the machine, to completely cover the portions of the wire in advance of the dies. In conventional die block structures, sediment becomes trapped in the support adjacent the dies, frequently causing misalignment of the dies.

Another object of the invention is to overcome these difficulties by providing substantially uninterrupted paths for the drawing compound through the die block.

With these and other objects in view, the invention comprises a die block for wire drawing machines including fixedly positioned parallel members with aligned apertures in the path of the wire to be drawn and spaced projections carried by one of the members for a die to rest thereon and to be positioned thereby, whereby the aperture of the die will be aligned with the path of the wire. More specifically, the spaced projections are pins circular in cross section, and as the die is of a similar cross sectional contour, the drawing compound may circulate freely by gravity and there are no pockets or ledges where sediment may accumulate.

Other objects and advantages will be apparent from the following detailed description when considered in conjunction with the accompanying drawings, wherein:

Fig. 1 is a schematic illustration of a wire drawing machine embodying the invention;

Fig. 2 is a side elevational view of the die block;

Fig. 3 is a vertical sectional view taken along the line 3—3 of Fig. 2; and

Fig. 4 is an isometric view of the die block.

Referring now to the drawings, attention is first directed to Fig. 1 which illustrates a wire drawing machine having a supply spool 10 of the wire 11 to be drawn. The wire 11 travels upwardly over a sheave 12 and around stepped capstans 14 and 15 of the top unit, after which the

wire travels over a sheave 16 to the lower unit. The lower unit is substantially identical to the upper unit with the exception of the diameters of the steps of the capstans 17 and 18 and, of course, the sizes of the dies supported by the die blocks 19 and 20. The finished wire, upon leaving the lower unit, travels around a sheave 21 to a take-up reel 22. A wire drawing compound 24 is supplied so that it will travel by gravity through the die blocks 19 and 20 and over the capstans 15 and 17 on one side and 14 and 18 on the other.

The invention is embodied in the die blocks 19 and 20 which are substantially identical in structure, the only difference being in the sizes of the die cavities to bring about the required reduction in the wire as it passes through the successive dies. A description of the die block 19 will apply equally well to the die block 20. Attention is now directed to Figs. 2, 3, and 4, which illustrate the die block having a mounting plate 29 secured to the main frame or housing of the machine and having a central member 30 or main support fixed thereto. The member 30 is of the contour shown and is provided with a plurality of apertures or notches 31 adjacent the paths of the portions of the wire 11 traveling in straight lines between the steps of the capstans 14 and 15. Dies 32, circular in cross section, have passageways or cavities 33 and in the present embodiment of the invention these dies are also provided with the usual diamonds to assure accurate, long wearing dies.

By viewing Figs. 3 and 4, it will be apparent that two groups of dies are positioned out of alignment with each other on opposing sides of the main member 30. Supporting means is therefore provided on each side of the member 30 for each die. The supporting means includes three projections or pin-like elements 35, circular in cross section and spaced in arcuate arrangement so that each die may rest in its open nest or group of projections and have its cavity in alignment with the portion of the wire to pass therethrough. The projections 35 have their inner ends embedded in apertures of the main member 30, and through the staggered arrangement of the dies, the supporting pins or projections on one side will not interfere with those on the other side of the main member 30.

Outer members 37 and 38 are fixed to the main member 30 by bolts 39 while spacers in the form of sleeves 40 assure accurate spacing of the outer members from the main member 30 and also from

55 the dies 32.

Consider now the function of the die block with the structures illustrated in Figs. 2 to 4 inclusive mounted in the machine as shown in Fig. 1. During the normal operation of the machine, the various portions of the wire are advanced by the rotation of the capstans, pulling these portions through their respective dies 32. While the drawing compound 24 drops by gravity through the open die blocks 19 and 20, the members 30, 31, and 38 of the die blocks are parallel with each other and with the path of the drawing compound 24, permitting the compound to travel freely through the areas wherein the dies are located. The dies 32 in the present embodiment of the invention are not housed in structures completely surrounding them, but are supported in open structures free to receive and be completely surrounded by the drawing compound. The supporting means for the dies include only the pins 35 suitable to provide nests for the dies requiring the smallest surface contacts with the dies for free travel of the drawing compound and the elimination of areas where sediment may accumulate. Furthermore, the dies 32 in resting on their pins 35 are freely accessible should it be necessary to remove any of the dies permanently or temporarily from the die block.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. A die block, for dies circular in cross section for each wire drawing position, mounted in a wire drawing machine in a path of a wire drawing compound fed by gravity to the dies and portions of a wire being drawn thereby, the die block comprising a vertically positioned main support having a surface lying in a given plane, and individual nests for the circular dies composed solely of sets of spaced pin-like members supported by the main support, extending laterally from the surface thereof and being smooth surfaced whereby the drawing compound may travel freely through the die block and about the dies and wire portions free of any retaining pockets.

2. A die block, for dies circular in cross section for each wire drawing position, mounted in a wire drawing machine in a path of a wire drawing compound fed by gravity to the dies and portions of a wire being drawn thereby, the die block comprising a vertically positioned main support having a surface lying in a given plane, and individual nests for the circular dies composed solely of sets of spaced pin-like members supported by the main support, extending laterally from the surface thereof and being smooth surfaced whereby the drawing compound may travel freely through the

die block and about the dies and wire portions free of any retaining pockets and a vertically positioned element mounted adjacent to but spaced from the pin-like members of the nests to maintain the dies against displacement relative to their nests longitudinally of the wire portions.

3. A die block, for dies circular in cross section for each wire drawing position, mounted in a wire drawing machine in a path of a wire drawing compound fed by gravity to the dies and portions of a wire being drawn thereby, the die block comprising a vertically positioned main support having side surfaces lying in parallel planes and apertures for the wire portions, and individual nests for the circular dies composed solely of sets of spaced pin-like members supported by the main support and extending laterally from out of aligned portions of their parallel surfaces and being smooth surfaced whereby the drawing compound may travel freely through the die block and about the dies and wire portions on both sides of the main support free of any retaining pockets.

4. A die block, for dies circular in cross section for each wire drawing position, mounted in a wire drawing machine in a path of a wire drawing compound fed by gravity to the dies and portions of a wire being drawn thereby, the die block comprising a vertically positioned main support having side surfaces lying in parallel planes and apertures for the wire portions and individual nests for the circular dies composed solely of sets of spaced pin-like members supported by the main support and extending laterally from out of aligned portions of their parallel surfaces and being smooth surfaced whereby the drawing compound may travel freely through the die block and about the dies and wire portions on both sides of the main support free of any retaining pockets and vertically positioned elements mounted adjacent to but spaced from their respective pin-like members to maintain their respective dies against displacement relative to their nests longitudinally of the wire portions.
